Townsend & Decker.

UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

LOCK.

Application filed December 31, 1919. Serial No. 348,584.

To all whom it may concern:

Be it known that I, SAMUEL SEGAL, a citizen of the United States, and a resident of New York, in the county of New York and 5 State of New York, have invented certain new and useful Improvements in Locks, of which the following is a specification.

My invention relates to locks of the swinging door type and has for its object 10 the production of a lock of simplicity of construction which shall be so constructed as to prevent an unauthorized entrance through the door by a "jimmying" of the lock or by other means.

15 Other objects of the invention will be apparent from the accompanying description setting forth the details of construction of the invention, the invention consisting more particularly in the novel parts and combinations of parts hereinafter described and then specified in the claim.

In the accompanying drawing showing a practical embodiment of the invention:

Fig. 1 is a front elevation of my improved lock shown applied to a door.

Fig. 2 is a rear elevation of the lock with its cover plate removed.

Fig. 3 is a horizontal section on the line 3—3 of Fig. 4.

30 Fig. 4 is a vertical cross-section on the line 4—4 of Fig. 3.

Fig. 5 is a perspective view of the lock keeper.

Referring in detail to the several figures 35 of the drawing:

1 indicates a door and 2 the door jamb or wall adjacent the door. A casing 3 containing the locking mechanism is provided with a removable cover plate 4, the casing 40 being fastened to the inner face of the door preferably by suitable screws 5 as shown.

The end of the casing extends inwardly an appreciable distance over the space between the door and door jamb, that portion 45 of the casing which registers with and preferably enters the space between the door and door jamb when the door is closed being solid and provided with a rib or beaded portion 6 (see Fig. 3). Thus if a tool

50 or jimmy is inserted within the space between the door and door jamb in an attempt to dislodge or break the lock, it will merely strike against the beaded or reinforced

solid portion 6 and will not strike against 55 or engage the mechanism within the lock

or the edge of the casing as is usually the case.

7 and 8 indicate opposed locking bolts which are pivotally mounted at their ends, as at 7', 8', within the casing 3. Said 60 locking bolts are provided with thickened or enlarged portions 9 and 10 adjacent their pivoted ends, and their opposite ends terminate in heads 11 having inner bevelled edges as illustrated. The said locking bolts 65 7 and 8 are also connected together by a spring 12 the action of which tends to draw them, or cause them to swing, towards each other on their pivots 7' and 8' into engagement with the posts or stops 13 which are 70 mounted in the wall of the casing.

A keeper, the body of which comprises an angle piece and which is indicated at 14, is secured to the corner of the door jamb by suitable screws as shown and preferably 75 countersunk therein. Extending inwardly from said angle piece is a transverse member 15 having a vertically extending member 16 secured thereto and forming hooks with said transverse member. Said member 16 has an outer curved surface as clearly shown in Fig. 5. All the parts of said keeper are preferably cast as a single integral structure.

The casing 3 is provided adjacent its inner solid side wall 17 with a slot 18 extending completely through both the front and rear wall of the casing through which slot the hooked end of the keeper is adapted 80 to extend as shown in Fig. 1. Thus, if a jimmy or other tool were inserted in the space between the door and door jamb and by any possibility extended through the slot 18 instead of striking the reinforced beaded portion 6, a breaking or displacement 85 of the casing would still be impossible by lateral or vertical pressure, as the jimmy or tool would contact with the closed walls of the slot 18 when the displacement of the casing is attempted and would 90 accordingly prevent the same. This is a distinct advantage over certain previous forms of casings having a slot open at their outer side, through which the keeper extends, and which may be laterally "jimmied" inwardly 95

100 in an obvious manner as there is no obstruction to provide a stop for the jimmy or tool.

19 indicates the face plate and 20 the tumbler barrel of a cylinder lock of the well 110

known type which is anchored as is customary, to the casing by suitable bolts 21. Extending through the casing and through a cam 22, which it is adapted to actuate, is the operating spindle 23. 24 indicates a latch knob which is mounted on the casing and the shank of which extends through the wall thereof, said shank carrying on the end thereof a second cam 25 similar in configuration to said cam 22. As the cams 22 and 25 engage the thickened or enlarged portions 9 and 10 of the locking bolts 7 and 8 these bolts may be operated by means of a key inserted in the face plate 19 of the cylinder lock and turned therein or by turning the latch bolt 23 on the inside of the door whereby the cams are actuated in an obvious manner. The configuration of the cams is such, that when either is turned through an angle of 45° or to a position at right angles to that shown in Fig. 2, the locking bolts 7 and 8 are in open position and are held in that position by the cam until it is again turned in either direction.

25 When the door is open and the locking bolts are in normal position or that position shown in Fig. 2, the door may be automatically locked by merely closing the same without its being first necessary to manually spread the bolts apart or move them away from each other. On the closing of the door the inner bevelled edge of the heads 11 of the locking bolts strike against the curved surface of the vertically extending member 16 of the keeper along which they move in opposite directions against the action of the spring 12 and finally ride over the top and

bottom edges of the vertically extending members and are brought into engagement, due to the action of the spring 12, with the transverse member 15 of the keeper in an obvious manner.

What I claim as my invention is:

In a lock, the combination with a keeper comprising a transverse member and a vertical member secured thereto having an outer curved surface, of a lock casing adapted to be fastened to a door with the end of said casing extending over the space between the door and door jamb and presenting a solid wall to said space, said casing being provided with a slot extending completely therethrough and having closed walls through which slot the keeper extends, a pair of separate locking bolts independent of each other and pivoted within the casing and having bevelled heads adapted to strike against and ride over the curved surface of the vertical member of said keeper whereby said locking bolts will automatically interlock with the keeper upon the closing of the door, a cam mounted in said casing intermediate said locking bolts and independent thereof and engaging the same and a spring fastened to and connecting said locking bolts and tending by its action to draw them towards each other.

Signed at New York, in the county of New York and State of New York, this 30th day of December A. D. 1919.

SAMUEL SEGAL.
